UNITED STATES PATENT OFFICE.

FREEBORN F. RAYMOND, 2d, OF NEWTON, MASSACHUSETTS, ASSIGNOR, BY MESNE ASSIGNMENTS, TO THE UNITED SHOE MACHINERY COMPANY, OF NEW JERSEY.

HEEL-NAILING MACHINE.

SPECIFICATION forming part of Letters Patent No. 650,420, dated May 29, 1900.

Application filed November 11, 1889. Serial No. 329,857. (No model.)

To all whom it may concern:

Be it known that I, FREEBORN F. RAYMOND, 2d, a citizen of the United States, residing at Newton, in the county of Middlesex and State 5 of Massachusetts, and having my post-office address at West Newton, in the same county and State, have invented a new and useful Improvement in Heel-Nailing Machines, of which the following is a full, clear, and exact description, reference being had to the accompanying drawings, forming a part of this specification, in explaining its nature.

The invention is an improvement upon that described in my Letters Patent of the United States dated February 14, 1899, No. 619,707; and it relates especially to the devices for presenting the work to the nail-driving and top-lift-spanking appliances, whereby the construction of the jacking mechanism is 20 simplified and the machine adapted to be fed with shoes from the back of the machine as well as from the front.

Referring to the drawings, Figure 1 is a view, part in vertical section from side to 25 side and part in front elevation, of a machine having the features of my invention. Fig. 2 is a view in vertical section, taken from front to rear, of the machine. Fig. 3 is a view in horizontal section upon a line between the 30 nailing devices and the jacks and in plan of parts below said line. Fig. 4 is a view representing the same portions of the machine represented in Fig. 3, but in a different position. Fig. 5 is a view in elevation, enlarged, 35 of the upper part of the machine, including the cross-head and rotary head and head-turning mechanism. Fig. 6 is a view in rear elevation of a portion of the head-turning mechanism. Fig. 7 is a view in elevation of 40 the rotary head detached from the cross-head.

A is the frame of the machine. Its sides a a' and cross bed or piece a² are integral or in one casting.

B is the cross-head. It carries the rotary 45 head b, preferably having three groups of operating devices, each of which groups comprises the heel-nailing apparatus b' and the top-lift spanker b². As these appliances are described in said patent, I need not further 50 refer to them here. I would say, however, that so far as the principal features of the

present invention are concerned it is not necessary to employ more than one group of operating devices and in some instances only* the heel-attaching devices.

C is the shaft of the machine. It has the cranks c c', which are connected with the cross-head B by the connecting-rods c² c³. The shaft is supported by bearing-blocks c⁴, bolted to the bed or cross-piece a².

D is a fly-wheel which also serves as a pulley. It is secured to the main shaft C, and the shaft has the outer bearing d in the standard d'. d² is a member of the clutch on the fly-wheel, and d³ is a member of the clutch 65 on the shaft. It is operated as follows: d⁴ is a lever pivoted at d⁵ and forked at its upper end to support rolls to enter the groove d⁶ in the member d³ of the clutch. d⁷ is a spring which serves when the lever d⁴ is released to 70 move the member d³ of the clutch into engagement with the member d². It extends from the lower end of the lever to the frame of the machine. d⁸ is a latch-lever pivoted at d⁹ to the lever d⁴, having the latch d¹⁰ and 75 connected at its end d¹¹ by the rod d¹² with the treadle d¹³. A spring d¹⁴ serves to hold this latch-lever up. The lever d⁴ is pivoted upon the end of the shaft d¹⁵. This shaft carries a gear d¹⁶, which makes one revolution for 80 every two of the gear d¹⁷ upon the shaft C. Upon the outer face of the gear d¹⁶ is a cam d¹⁸, placed to be moved into contact with the latch d¹⁰ of the latch-lever. The operation of this part of the machine is as follows: Upon 85 depressing the treadle the latch-lever is moved downward and the latch moved out of line with the stop-cam d¹⁸. This enables the spring d⁷ to act to move the member d³ of the clutch into engagement with the member d². Upon 90 the release of the treadle d¹³ the spring d¹⁴ immediately draws the latch-lever upward and the latch into position to be operated by the cam-stop d¹⁸, which upon the revolution of the gear d¹⁶ is brought against its edge and 95 moves the lever d⁴ to disengage or move outward the section d³ of the clutch and to also release the tension upon the operating-spring d⁷. This construction is quite analogous to that described in my said patent, varying 100 therefrom only in a slight detail of construction, which, however, has some features of

value, in that it is somewhat simpler in construction and more direct in its operation.

The cross-piece a^2 of the frame has integral with it or supports a bed E. This bed has 5 preferably a flat upper surface e, in which is arranged a guideway e', extending from front to back of the machine. In this guideway is secured a long plate e², preferably by means of cap-plates e³, and there is secured to this 10 plate e² by means of bolts the jacks F F'. The extent of forward movement or movement toward the rear of the machine of the plate e² is limited by the rear adjustable stop f and the lug or stop f', formed on or attached to the 15 plate. The reverse movement or movement toward the front of the machine is limited by the adjustable stop f² and the said lug or stop f', carried by the plate, both sides of which are, it will be seen, utilized as stops in connection with the adjustable stops f f². The 20 jacks are made adjustable upon the said plate E by means of the slots f³ in their base-sections and the attaching-bolts f⁴, so that the jacks are movable toward and from each other 25 on the plate and are adjustable in relation to the plate. Each jack preferably comprises the base f⁵, the sleeve f⁶, extending upwardly therefrom, the spindle f⁷, guided and held by said sleeve, and the adjusting-nut f⁸ on the 30 lower threaded end of the spindle. Each spindle supports the lasts f⁹.

In operation the operator at the front of the machine places a shoe upon the last of the forward jack, which is then in its advanced 35 or forward position, the rear jack being under the nailing devices. He or the assistant then pushes or pulls the jack-plate to move the forward jack under the nailing devices. This moves the rear jack to the rear of the 40 machine and in a position to permit the assistant at the rear to place a shoe upon the last of said jack. While this is being done the operator has started the machine, attaching the heel and top lift, if used, to the first 45 shoe, and at the completion of the nailing, the second or rear last having a shoe in position, the jack-supporting plate is moved back again, moving the front jack out of operative position with the nailing devices and the rear 50 jack into operative position, and the machine is again started, the operator then removing the heeled shoe and substituting an unheeled, while at the completion of the second nailing the plate is again moved toward the rear of 55 the machine, the second heeled shoe removed from the rear last, another unheeled substi-

tuted therefor, and the movement proceeds as before. By this construction the work is placed or fed to the machine both from the front of the machine and from the rear in 60 successive order, and its capacity is thus very considerably increased.

I prefer in a machine of this organization to use loaded heel-blanks and to feed the loaded heel-blanks and top lifts substantially 65 as described in my said patent.

I have described the construction of the clutch mechanism in detail in the foregoing specification, indicating the separate parts thereof, but I do not desire in this application to make any claim therefor, and such description is for the purpose of more clearly 70 explaining the operation of the machine.

Having thus fully described my invention, I claim and desire to secure by Letters Pat- 75 ent of the United States—

1. The combination in a heel-nailing machine of heel-nailing devices, a sliding jack-support and two horizontally-adjustable jacks carried thereby, adapted to be adjusted to- 80 ward and from each other, and also to be brought alternately into operative position with relation to the nail-driving devices, sub-stantially as described.

2. In a heel-nailing machine, the combina-tion of a plate or bed extending across the frame of the machine from front to rear, a support for the jacks on said plate or bed, means for adjusting the jacks and stops for limiting the movements of the jack-support- 90 plate in both directions, substantially as described.

3. In a heel-attaching machine, the com-bination with a reciprocating cross-head; of 95 a heel-attaching device and a top-lift-attach-ing device mounted on said cross-head in dia-metrical opposition to each other, said heel and top-lift attaching devices being vertically reversible on said head; a jack-support be-neath said head adapted to be reciprocated 100 in a right line beneath the heel and top-lift attaching devices; and horizontally-adjust-able jacks or work-supports carried by said jack-support, said jacks or work-supports be-ing brought into operative relation to said 105 heel-attaching devices alternately as the jack-support is reciprocated.

FREEBORN F. RAYMOND, 2D.
